DOOR PROTECTOR PLATE

Frederic C. Bennett and Sandra J. Bennett, both of 61647
Meadowlark Lane, South Bend, Ind. 46614

Filed Feb. 1, 1972, Ser. No. 222,723

Term of patent 7 years

Int. Cl. D8—09

U.S. Cl. D8—137

FIG. 1 is a perspective view of a door protector plate embodying the present design;

FIG. 2 is a front elevational view of the door protector plate illustrated in FIG. 1;

FIG. 3 is a bottom edge view of the door protector plate illustrated in the preceding figures; and

FIG. 4 is a rear elevational view of the door protector plate shown in the preceding figures.

We claim:

The ornamental design for a door protector plate, substantially as shown.
